GUARD FOR TRIGGER SWITCHES

Filed Aug. 13, 1929

FIG. 2

Elanathan Alfred Fowler ^{Inventor}
By *Permen E. Stangell*
His ^{attorney}

UNITED STATES PATENT OFFICE

ELNATHAN ALFRED FOWLER, OF YORK, PENNSYLVANIA, ASSIGNOR TO THE FLOOROLA CORPORATION, OF YORK, PENNSYLVANIA, A CORPORATION OF DELAWARE

GUARD FOR TRIGGER SWITCHES

Application filed August 18, 1929. Serial No. 385,605.

This invention relates to an improvement in guards for trigger switches.

The object of the invention is to provide a guard for a trigger switch of the general type usually employed on floor polishing and similar machines, in which the switch is ordinarily carried by the handle. The guard is provided to receive and act as a stop for the trigger, thereby preventing the trigger from being moved too far or moving sideways, thus eliminating any danger of bending the trigger or destroying the switch and also making the switch more restful to the finger of the operator.

In the accompanying drawings:

Fig. 1 is a perspective view illustrating the guard as applied to the handle; and

Fig. 2 is a top plan view of the guard.

The numeral 1 indicates the handle of the floor polishing or other similar machine to which the plate 2 is secured by means of the screws 3. Screws 4 extend through the plate 2 to secure the switch thereto, which switch is mounted beneath the plate and within the handle 1.

The guard plate 2 is provided with a slot 5 therein, upon the opposite side of which are the flared portions 6, and the trigger 7, which is attached to and operates the switch, extends through the slot 5 as shown in Fig. 1.

The guard is designated generally by the numeral 8 being provided with the flanged sides 9 and is secured to the plate 2 at its lower end. The guard is curved substantially throughout its length to correspond approximately to the curvature of the trigger 7.

The guard is also provided with a slot or opening 10 approximately in the center thereof through which the trigger 7 may extend when it is in the retracted position and in which position it is held against sidewise movement by the flanges 11 of this opening 10. The guard also acts to prevent extreme movement of the trigger beyond the point of the guard and it serves as a hold for the operator in grasping the trigger and eliminates any danger to the trigger or switch as well as making the

switch more restful to the finger of the operator.

I claim:

1. A guard for an electric switch including a plate and a guard member extending outwardly therefrom and provided with an opening therein for receiving a portion of the switch.

2. A device of the character described including a plate adapted to be associated with an electric switch and having an opening therein, through which a trigger of the switch may extend, a guard carried by the plate and extending outwardly therefrom and having a slot formed therein in position to receive the trigger of the switch.

3. A device of the character described including a plate adapted to be associated with an electric switch and having a notch formed therein, through which a trigger of the switch may extend, the portions of the plate at the opposite sides of the notch being flared to facilitate movement of the trigger and a guard carried by the plate and extending outwardly therefrom, said guard being curved to approximately correspond to the curvature of the trigger and being provided with a flanged slot formed therein to prevent extreme movement of the trigger and destruction to the switch.

In testimony whereof I affix my signature.

ELNATHAN ALFRED FOWLER.
